WRINGER MOP

Conrad Fatland, Mount Prospect, Ill.

Application April 27, 1937, Serial No. 139,223

2 Claims. (Cl. 15—120)

This invention relates to wringer mops, and it has for one of its objects to provide for wringing the mop cloth out removing it from the head, and the arrangement is such that the cloth can be wrung without any manipulation of the mechanism. Other objects of the invention will appear from a consideration of the accompanying drawings and the following description thereof.

Of the drawings, Fig. 1 is an elevation of a mop frame and handle without the cloth, which embodies the features of my invention; Fig. 2 is a side elevation of the same; Fig. 3 is a sectional view along the line 3—3 of Fig. 1; Fig. 4 is an enlarged view of the cloth clamping mechanism; Fig. 5 is a sectional view along the line 5—5 of Fig. 1; Fig. 6 is an elevation of the head and cloth as the cloth is being wrung; Fig. 7 is an enlarged view of a modified clamping mechanism; Fig. 8 illustrates the method of grasping the handle when mopping; and Fig. 9 illustrates the method of grasping the handle as the cloth is being wrung. Figs. 10 to 13 illustrate a modified form of mop.

The mop complete comprises a handle 10, a frame or head 11, and the cloth 12, and includes a rod 13 for wringing the cloth. The head comprises a yoke like member 14, which, by means of a loop 15, is fixed to the inner end of the handle by any suitable means, such as the plate 16 and the bolts 17. Preferably integral with one arm 18 of the yoke is a bar 20 for supporting the inner end of the mop cloth 12. This bar has a hook or eye 21 on its free end which is adapted to receive a hook 22 formed on the outer end 35 of the arm 23 of the yoke. When the cloth is to be inserted the hook is forced out by springing the resilient bar inwardly. The looped end of the cloth is then passed over the end of the bar and the hook is inserted in the eye 21.

The outer end of the head is attached to the handle by means of the rod 13. This rod projects through an eye in the flange 24 of the plate 16, and the rod projects beyond the inner end of the handle 10. Pivoted to the inner end of the rod 13 is another rod 25', and this rod supports the portion of the head which is arranged to hold the outer end of the mop cloth. This portion comprises a bar 25 having flanges 26 projecting from its ends. A bar 27 has its ends pivoted to these flanges, and this bar has an angularly projecting portion 28, which, when the cloth 12 is inserted between it and the bar 25, is adapted to clamp the cloth against the bar 25. This is accomplished by means of a handle 30. When the handle is pressed downwardly against the rod 25',

carrying with it the outer edge of the bar 27, to which the handle is attached, the bar portion 28 forces the cloth end against the bar 25.

When the cloth is thus inserted and clamped the mop is ready for operation. In operation the cloth 12 is laid flat on the floor and the handle is inclined upwardly as much as the operator may desire. As will be seen, the arrangement is such that no portion of the metal of the head comes in contact with the floor, and also the handle 10 is free to turn on the pivot 31, as much as the operator may desire, without disturbing the cloth.

While mopping the hand is grasped around the plate 32, which is fixed to the outer end of the handle 18, and the hand also grasps the arm 35 fixed to the outer end of the rod. The other hand of the operator grasps the handle wherever desired. Thus in operation one hand firmly holds the outer end of the handle 10 by means of the plate 32 and thus prevents rotation of the rod 13 relative of the handle. This rod 13 passes rotatably through the U-shaped plate 32 and also along a groove 33 extending longitudinally of the handle; so that it is no inconvenience to the operator when the mop is operated.

When the cloth is to be wrung the operator grasps the outer end of the handle 10 and the plate 32, as indicated in Fig. 9, preferably by the left hand, and with the other hand he grasps the arm 34 of the handle 35, and rotates the rod 13 so as to twist the cloth around the wringing rod 25' as indicated in Fig. 6. Although the cloth is free to pivot angularly with reference to the handle when mopping, yet, when wringing, the cloth always assumes a position in line with the handle. This is because the distance of the bar 25 from the pivot 31 of the rod 13 is greater than its distance from the rod 20 which holds the inner end of the cloth, and hence any angular movement of the cloth tends to stretch it.

In Fig. 7 I illustrate a modified clamping means. This comprises an angular bar 36 which is fixed to the outer end of the rod 25', taking the place of the bar 25. Pivoted to the ends of the bar 36 are bars 37 which are fixed to the ends of a bar 38, and fixed to the bar 38 is a handle 39. When the outer end of the cloth 12 is inserted between the bars 36 and 38, by turning the handle down against the rod 25' the cloth is clamped between the two bars. In order to prevent inadvertent separation of the bars a pin 40 is passed through openings in the outer ends of the flanges 26 on the end of the handle 39.

The stop 24 not only acts as a bearing for the rod 13, but it acts as a stop to limit the backward

movement of the rod and hence the clamp 25-28. If desired the pivot 31 may be positioned against the stop, so that there will be no backward movement of the clamp.

5 Figs. 10 to 13 illustrate modifications of the mop. The cloth clamp 40' may be in all respects similar to the clamp 25-28. But in this instance I have shown it similar to the clamp of Fig. 7. The rod 41' supports the inner end of the mop

10 cloth. In inserting the cloth the central portion is looped around the rod, and the two ends are then clamped in the clamp 40'. The ends of the looped rod are inserted in the tube-like eyes 42 of a collar 43. The collar is rotatably mounted on 15 the handle 44, and the collar is held in place by the collars 45 and 46 which are fixed to the handle. The ends 47 of the looped rod 41 are bent outside of the collar eyes 41 so as to prevent outward movement of the rod.

15 20 In wringing the clamp 40' holds the outer end of the mop cloth from rotation with reference to the handle by means of the supporting rod 43, which is pivoted to the inner end of the handle 44 by means of a pivot 49 which also holds the 25 collar 45. The operator grasps the collar 43 by one hand, preferably the left, and then with the right hand rotates the handle in the collar. The eyes 42 assist the operator in preventing rotation of the collar. In this manner the inner end of 30 the cloth is rotated with reference to the outer end and the cloth may be very thoroughly wrung as it is twisted around the wringing rod.

35 In operation while mopping the cloth lays on the floor, as in case of the other modification, and the pivoted end of the rod 43 allows any desired angle between the cloth and the handle.

40 In the claims the word inner refers to that portion of the handle, rod, or cloth which is nearer the central portion of the apparatus, and the word outer refers to that portion which is furthest from the central portion.

Instead of the ordinary annular sleeve or collar, I prefer a U-shaped collar 43 for carrying the cloth holding loop, so as to enable the operator

to more easily retain the hand grip on the collar when rotating the handle within the collar. By turning a substantial portion of the outer portion of each arm of the collar inwardly I provide means whereby two parallel parts of the mop cloth holding loop are retained so as to prevent the loop from rotating independently of the U-collar, and the inward turning of said arms also affords a better hand-grip.

5 Flat surfaces on the rods 25' and 43 in contact with similar flat surfaces on their pivot supports establish a degree of rigidity which prevents the rod and mop cloth from swinging laterally when mopping. And means are provided whereby the mop cloth always assumes a position substantially in line with the handle when it is being wrung. Otherwise the bars 25' and 43 would be rotated out of alignment by the pull incident to the wringing operation, and it would be practically impossible to twist the cloth tightly. In Figs. 1, 2, and 6, bar 20 is so positioned with reference to the desired alignment as to properly limit the movement of the rod 25' out of alignment in one direction; and in Figs. 10 to 13, the shoulder 50 forms the limiting means. Also in these latter figures the bar 41' might serve as a limiting means if the stop 50 were omitted.

I claim as my invention:

1. In a mop, a handle, a rod pivoted by one end to the inner end of the handle and having a mop cloth holding means at its free end, a collar rotatably mounted on the inner end of the handle and having attached thereto a cloth holding bar positioned transversely of the said rod between the pivot and its free end, said rod and bar being relatively rotatable substantially coaxially with the handle.

2. In a mop as claimed in claim 1, and means to prevent pivotal movement of the rod in one direction about the axis of the pivot beyond a position substantially in axial alignment with the handle.

CONRAD FALAND.
